CLAIM

I claim the ornamental design for a football helmet sweatshirt, as shown and described.

DESCRIPTION

FIG. 1 is a perspective view of a football helmet sweatshirt showing my new design;

FIG. 2 is a perspective view thereof shown in an alternate position of use;

FIG. 3 is a front elevation view thereof;

FIG. 4 is a rear elevation view thereof;

FIG. 5 is a right side elevation view thereof; the left side being a mirror image thereto;

FIG. 6 is a top plan view thereof; and,

FIG. 7 is a bottom plan thereof.

The broken lines shown in the figures illustrate unclaimed environmental subject matter and form no part of the claimed design.
